UNITED STATES PATENT OFFICE.

HAROLD CHRISTENSON, OF SAVANNAH, GEORGIA.

PEDAL-ACTUATING DEVICE.

Application filed May 10, 1927. Serial No. 190,284.

This invention relates to devices for operating the pedals of automobiles, and particularly the accelerator thereof, and the general object of the invention is to provide 5 a device of this kind which will not only support the foot in proper operative relation to the accelerator pedal but eliminate the necessity of holding the leg and ankle in a tense and strained position.

10 A further object is to provide a device of this character which will support the foot out of direct contact with the accelerator or other pedal but which will actuate the pedal by a slight rolling movement of 15 the ankle or sway of the knee and which will permit relaxing of the body.

A still further object is to provide means 20 which will form a firm rest for the foot, which at the same time will give a perfect control of the accelerator pedal and throttle and which will prevent wastage of gasoline or other fuel due to the more or less constant opening and closing movement of the 25 throttle, in turn due to the jars and oscillations of the car.

Another object is to provide a device of 30 this character which is very simple, which may be readily attached to the foot board of the car, and which may be used not only for the accelerator pedal but for starting 35 pedals.

My invention is illustrated in the accompanying drawing, wherein:—

Figure 1 is a top plan view of my pedal 40 actuating device;

Figure 2 is a side elevation thereof;

Figure 3 is a like view to Figure 2 but showing the pedal actuating device and 45 pedal depressed;

Figure 4 is a section on the line 4—4 of 50 Figure 2.

Referring to this drawing, it will be seen 55 that my device comprises a base 10 and crossed members 11 and 12. The member 11 at its lower end is hinged to the base by the pintle 13 and the member 12 is longitudinally slotted, as at 14, or otherwise formed so as to permit the member 11 to pass through this slot and thereby cross the member 12. The lower end of the member 12 is hingedly connected to the base 10 by means 60 of the pintle 15 and the upper ends of both of the members 11 and 12 are hingedly connected to a plate 16. This plate 16 has 65 mounted thereon or has formed therewith the lateral extension or lip 17 which is

adapted to engage over the accelerator pedal A. Preferably the upper face of the plate 16 is provided with a cushion or pad 18 of rubber or like material so that the foot will 70 not slip upon this actuating device.

It will be seen that downward pressure will not change the position of the foot plate 16 or its pad but that a rocking movement in either direction will cause the foot supporting plate to be depressed toward the left or toward the right, depending entirely upon the rocking movement communicated thereto, and that as in Figure 3 a rocking movement of the foot will cause the depression 75 of the left hand end of the plate 17, which will cause the depression of the accelerator A. The device will also rock downward at its other end upon a rocking movement of the foot so that the device may be 80 used to depress either an accelerator pedal or depress a starting pedal, for instance.

This device supports the foot firmly and the shocks and jars of the car will not cause the foot to continually reciprocate the accelerator pedal but the accelerator pedal will 85 only be operated when the foot is rocked or by a rocking movement of the knee or ankle. The line of gravity in this device changes automatically so that there is always a firm rest for the foot, thus giving 90 perfect control of the throttle. The foot accelerator in general use is a gasoline waster because of the constant opening and closing of the throttle due to the varying pressures exerted by the toe of the foot on the accelerator, which pressures vary with the movements of the car. My device will, therefore, 95 save gas by not permitting any oscillations of the foot applied directly to the accelerator pedal. Furthermore, when the wheels of a car hit holes or bumps, there is an almost instantaneous depression of the accelerator pedal which, of course, is bad for the driving gears, and this is eliminated by my 100 device.

This device can be placed in any position desired on the floor of the car or upon the foot board of the car and can be made long enough to extend lengthwise of the car and support the entire foot or as illustrated in the drawing. As shown, the device is disposed with its longitudinal axis at an inclination to the longitudinal axis of the car and upon the inclined foot board and this 105 I have found to be one of the most efficient ways in which the device may be mounted.

Inasmuch as the device is capable of tilting equally in either direction by the turning of the ankle, the starter buttons which are close to the floor boards may be readily reached by tilting this foot rest.

Preferably, and in order to hold the foot rest always against the accelerator pedal, I provide a spring 19 disposed between the base and the member 11 which lifts this member 11 and, therefore, forces the plate 17 into contact with the accelerator head, this spring being such that the tension will merely carry the plate into contact with the accelerator pedal head without acting to depress the accelerator. This device also permits the use of a very weak spring on the accelerator pedal, as this spring does not have to support the weight of the foot and thus a minimum of pressure will operate the accelerator.

It will be seen that this device is very simple and I have found it thoroughly effective in actual practice. Obviously it may be made in different forms and, therefore, I do not wish to be limited to the details of construction as defined in the appended claims. I have illustrated a spring as bearing directly against the head of the pedal, but it will be understood that this positioning of the spring is merely illustrative.

I claim:—

1. A pedal actuating device including two crossed members hingedly supported at their lower ends, a plate constituting a foot rest and hingedly connected to the upper ends of the crossed members whereby the upper plate may be tilted into depressive engagement with a pedal but cannot be bodily depressed.
2. A pedal actuating device including two crossed members hingedly supported at their lower ends, a plate constituting a foot rest hingedly connected to the upper ends of the crossed members, said plate having a portion projecting beyond the crossed members

and adapted to engage the head of a pedal, and a spring urging one of said members upward to cause the plate to engage said pedal.

3. A pedal actuating device of the character described including a base, crossed members hinged to the base, and a member constituting a foot rest and hingedly connected to the upper ends of the crossed members, said foot rest member having a projecting portion adapted to engage over the head of a pedal.

4. A pedal actuating device including a base, a slotted member hinged at its lower end to one end of the base, a second member hinged at one end to the other end of the base and extending up through the slot of the first named member in crossed relation thereto, a foot rest to which the upper ends of said crossed members are hingedly connected, said foot rest having an extended portion adapted to bear against the head of a pedal, and a spring urging one of said crossed members upward to thereby urge said extension downward against the head of the pedal.

5. The combination with a pedal, of means for actuating the pedal including a foot plate extending over the pedal and hingedly supported at its end remote from the pedal, and a support for said foot plate hingedly connected adjacent the free end of said foot plate and extending downward at an angle thereto and hingedly connected beneath the other end of the foot plate.

6. The combination with a pedal, of an actuating device therefor including a base, crossed members hinged at their lower ends to opposite ends of the base, and a foot plate hinged to the upper ends of said members and having an extension extending over the head of the pedal.

In testimony whereof I hereunto affix my signature.

HAROLD CHRISTENSON.
